UNITED STATES PATENT OFFICE.

JULIUS F. RADTKE, OF CHICAGO, ILLINOIS.

AUTOMATIC CALENDAR.

Application filed February 9, 1922. Serial No. 535,346.

To all whom it may concern:

Be it known that I, JULIUS F. RADTKE, a citizen of the United States, residing at Chicago, in the county of Cook and State of Illinois, have invented new and useful Improvements in Automatic Calendars, of which the following is a specification.

This invention relates to clocks having calendar attachments which are driven by the 10 clock train, the attachments being endless belts bearing the names of the days of the week, the names of the months, and the numbers of the days of the month, said belts being shifted at the proper time to display a 15 new inscription.

The invention has for its object to provide a calendar of the kind stated embodying certain novel and improved features of construction and modes of operation to be 20 hereinafter described and claimed, and in order that the same may be better understood, reference is had to the accompanying drawings, wherein:

Figure 1 is an elevation of the clock; Fig. 25 2 is a plan view of the calendar mechanism; Fig. 3 is a cross-section on the line 3—3 of Fig. 2; Fig. 4 is a cross-section on the line 4—4 of Fig. 2; Fig. 5 is an enlarged plan view of certain parts shown in Fig. 2; Fig. 30 6 is an enlarged elevation of a pawl-and-ratchet mechanism, and Fig. 7 is a similar view showing the parts in another position.

Referring specifically to the drawings, 10 denotes a clock of conventional design. The 35 clock case has a bottom compartment 11 which contains the calendar attachment, the face or front wall of said compartment having a display opening 12 through which are exposed for display the inscriptions on endless belts 13, 14 and 15, respectively. The belt 13 bears the names of the days of the week, the belt 14 the names of the months, and the belt 15 bears the numbers of the days of the month. The belts are arranged 45 in vertically spaced relation, and the width of the opening 12 is such that only one of the inscriptions is displayed at one time. The belts are shifted at the proper time to display the correct date, etc.

50 The belt 13 is trained over rollers 16 and 16^a, the belt 14 over rollers 17 and 17^a, and the belt 15 over rollers 18 and 18^a. Rollers

16, 17 and 18 are loose on a shaft 19, and rollers 16^a, 17^a and 18^a are loose on a shaft 19^a. The shafts 19 and 19^a are stationary, 55 they being suitably supported by top and bottom frame members 20 and 20^a in the compartment 11.

Pawl-and-ratchet devices are provided for periodically operating the rollers to feed the 60 belts. The devices for the rollers 16 will be described first.

On one end of roller 16 is fastened a ratchet wheel 21 and on the corresponding end of roller 16^a is fastened a ratchet wheel 21^a. A feed pawl 22 is engageable with the ratchet wheel 21, and the ratchet wheel 21^a is engageable by a feed pawl 22^a. Pawls 22 and 22^a are operated at the end of each day to turn the rollers 16 and 16^a a distance to feed the belt 13 past the display opening 12 and display thereat the name of the next day. The pawl 22 is operated by a gear wheel 23, and pawl 22^a is operated by a gear wheel 23^a. Gear wheel 23 has a 75 side lug 24 and gear wheel 23^a has a side lug 24^a. Between gears 23 and 23^a, and in mesh therewith, is a gear wheel 25 which is fastened to a shaft 26 obtaining motion from the clock train, preferably some element 80 thereof which will cause said shaft to make one complete revolution each day. It will therefore be evident that, through the gears 25, 23 and 23^a, and the pawl-and-ratchet mechanism, the belt 13 is advanced at the 85 close of the day a distance to display the name of the next day.

The gear wheels 23 and 23^a are fast on shafts 27 and 27^a supported by the frame members 20 and 20^a. 90

The belt 15 must also be advanced at the close of each day to display the new date, and hence the driving means may be the same as that employed for the belt 13. The roller 18 is therefore equipped with a ratchet wheel 28 engageable by a pawl 29, and the roller 18^a has a ratchet wheel 28^a engageable by a pawl 29^a. The pawl 29 has a laterally extending arm 30 which is in the path of a lug 31 on one side of a wheel 32 fast on 95 shaft 27. The pawl 29^a has a laterally extending arm 30^a which is in the path of a lug 31^a on one side of a wheel 32^a fast on 100 shaft 27^a. A second set of gear wheels 33,

33^a and 33^b, similar to the gear wheels 23 and 25 and 23^a may also be provided for transmitting the motion of shaft 26 to the shafts 27 and 27^a.

5 The pawl 29 has a longitudinal slot 34, through which extends a supporting rod 35 for the pawl, said rod extending between and being carried by the frame members 20 and 20^a. In the slot 34, between the rod 35 10 and the remote end of the slot, is located a coiled spring 36. When the lug 31 reaches the pawl arm 30, the pawl 29 is made to move backwards over a certain number of teeth of the ratchet wheel 28, this movement 15 of the pawl placing the spring 36 under compression. When lug 31 slips off arm 30, the pawl is advanced by the spring 36 the distance it was retracted, and the pointed end of the pawl now engages one of the 20 teeth of the ratchet wheel 28, thereby rotating the same and the roller 18 to feed the belt 15. The pawl 29^a, as well as the pawls 22 and 22^a are all operated in this manner, and hence the foregoing description 25 of the operation of pawl 29 is sufficient.

The rollers 17 and 17^a are also operated by a pawl-and-ratchet mechanism, the ratchet wheels being shown at 37 and 37^a, 30 and the pawls at 38 and 38^a. As the belt 14 is to be shifted only at the end of a month, the pawl 38 is operated by side lugs 39 on a gear wheel 40 loose on shaft 27 and obtaining motion from shaft 26 through a 35 suitable train of reducing gears as shown in Fig. 2. The pawl 38^a is operated by side lugs 39^a on a gear wheel 40^a loose on shaft 27^a, and also obtaining motion from the aforementioned train of reducing gears. 40 The pawls 38 and 38^a are supported and operated in the same manner as the pawl 29.

The gear wheels 40 and 40^a are designed to be given one revolution per year, and twelve properly spaced lugs 39 and 39^a are provided, so that the rollers 17 and 17^a may be given a step-by-step rotary movement to advance the belt 14 twelve times per year, or one step at the end of every month to display a new inscription. However, as the 45 number of days are not the same for all the months, a mechanism has been provided for shifting the date belt 15 through a space of one day that the months of April, June, September and November lack, and a space 50 of three days that the month of February lacks. For this purpose there is mounted between the pawl 29 and the gear wheel 28 a trip member 41 which is normally positioned to trip the pawl 29 off the teeth of the ratchet 55 wheel 28 on the backward stroke of said pawl, so that the pawl, on its working stroke, can move the ratchet wheel 28 only a distance corresponding to the number of teeth over which it had slipped on the backward 60 stroke. The parts are so designed that this

distance moves the belt 15 the correct distance to display the next date. If now, the member 41 is moved in the direction the pawl moves on the backward stroke, a larger 70 number of ratchet teeth will be exposed, so that the pawl, on its working stroke will turn the ratchet wheel a correspondingly greater distance. At the end of the month of February, the member 41 will be shifted to give the pawl a stroke long enough to 75 turn the ratchet wheel 28 a sufficient distance to advance the belt so that the numeral "1" will be displayed. For the thirty day months, the member 41 is shifted to allow the pawl-and-ratchet mechanism, at the end 80 of the thirtieth day, to advance the belt so that the numeral "1" will be displayed.

The shifting of the member 41 is automatically effected by providing the same with a projecting arm 42 which is in the 85 path of lugs 43 on the gear wheel 40 on the side opposite the one carrying the lugs 39. These lugs are so spaced angularly as to come into action at the proper time.

The member 41 is supported by rods 44 90 passing through a slot 45 in the rear end of said member, and a slot 46 in a lateral extension of the arm 42. Springs 48 in the slots 45 and 46 restore the member 41 to its normal position after the lugs 43 slip off the arm 42. It will be noted in Fig. 3 that one 95 of the lugs 43 is longer than the others, this being for the purpose of obtaining the maximum amount of retraction of the member 41 necessary for the month of February. 100

A pawl-tripping mechanism as hereinbefore described is of course also provided for the pawl 29^a.

I claim:

1. A calendar clock comprising endless 105 belts bearing inscriptions denoting days, dates and the names of the months, respectively, rollers over which the belts are trained, ratchet wheels for rotating the rollers, pawls for actuating the ratchet 110 wheels, clock-train driven rotatable members having lugs for engaging the pawls to actuate the same, the pawls associated with the days and dates belts being actuated daily, and the pawls associated with the months 115 belts being actuated monthly, a trip member in the path of the pawl of the dates belt and movable for varying the stroke of said pawl for shifting the dates belt an extra distance, and means on the rotatable member associated with the pawl of the months belt for actuating the trip member. 120

2. A calendar clock comprising endless 125 belts bearing inscriptions denoting days, dates and the names of the months, respectively, rollers over which the belts are trained, ratchet wheels for rotating the rollers, pawls for actuating the ratchet wheels, clock-train driven rotatable members having lugs for engaging the pawls to 130

actuate the same, the pawls associated with the days and dates belts being actuated daily, and the pawls associated with the months belts being actuated monthly, a trip member 5 in the path of the pawl of the dates belt and movable for varying the stroke of said pawl for shifting the dates belt an extra distance, and lugs on the rotatable member associated with the pawl of the months belt, into the path of which lugs the trip member 10 extends for actuation thereby.

In testimony whereof I affix my signature.

JULIUS F. RADTKE.
